UNITED STATES PATENT OFFICE.

ALBERT A. GORDON, JR., OF WORCESTER, MASSACHUSETTS, ASSIGNOR TO CROMPTON & KNOWLES LOOM WORKS, A CORPORATION OF MASSACHUSETTS.

WEFT-REPLENISHING LOOM.

Application filed March 17, 1922. Serial No. 544,583.

To all whom it may concern:

Be it known that I, ALBERT A. GORDON, Jr., a citizen of the United States, residing at Worcester, in the county of Worcester, 5 and State of Massachusetts, have invented a new and useful Weft-Replenishing Loom, of which the following is a specification.

This invention relates to a weft replenishing loom of the so-called "terry" type in which a looped uncut pile is formed by varying the forward position of the reed as different picks of weft or filling are beaten into the fabric.

More specifically, my invention relates 15 to a loom of this type in which the reed is fixed in the lay and the forward position of the entire assembly of lay and reed is varied on different beats of the lay.

It is the object of my invention to provide 20 a weft replenishing mechanism for a loom of this type so mounted and actuated that it will always maintain its operative relation in respect to the lay and to the shuttle and shuttle boxes thereon.

For the attainment of this object, my 25 improved magazine is movably mounted on the loom frame and is so connected with the terry motion that the position of the magazine is changed to correspond to the 30 forward or rearward adjustment of the locus of the lay movement.

In the preferred form of my invention not only the magazine but certain other 35 parts of the weft replenishing mechanism such as the weft detector and the thread holder are also mounted to move as a unit with the magazine as the latter is variably positioned.

My invention further relates to arrangements and combinations of parts which will 40 be hereinafter described and more particularly pointed out in the appended claims.

A preferred form of my invention is shown in the drawings, in which—

Fig. 1 is a side elevation of parts of a 45 loom embodying my improvements;

Fig. 2 is a detail sectional view taken along the line 2—2 in Fig. 1;

Fig. 3 is a front elevation of my improved 50 magazine and the supports therefor;

Fig. 4 is a detail rear elevation looking in the direction of the arrow 4 in Fig. 1; and

Fig. 5 is a detail side elevation looking in the direction of the arrow 5 in Fig. 3.

Referring to the drawings, I have shown

parts of a loom which are in general of the usual terry type comprising a loom frame 10, an arch 11, and a lay 12 mounted on swords 13 which swing about fixed pivots, not shown. The lay is moved forward and rearward in the usual manner by connecting rods 14 actuated from crank pins 15 in a crankshaft 16.

The bearings for the shaft 16 are eccentrically positioned in cylindrical bearing blocks 17 rotatably mounted in journal boxes 18. An arm 19 is fixed to each bearing block 17 and is connected by a link 20 to an arm 21 fixed on a cross shaft 22. An actuating arm 23 also fast on the shaft 22 is connected by 60 a link 24 to a stud 25 in a lever 26. The lever 26 is pivoted at 27 to a cross girt 28 and is periodically moved downward by engagement with a roller 29 on an arm 30.

The arm 30 rotates with a gear 31 driven 65 by a pinion 32 on the usual bottom or cam shaft 33 of the loom. As shown in the drawings, the gear 31 and pinion 32 are in the size relation of three to two. As the bottom shaft 33 rotates once for every 70 two beats of the lay, the lever 26 will be depressed once for every three beats of the lay.

It will be understood, however, that the 75 gearing ratio may be varied to produce a movement of the lever 26 once in any desired number of beats of the lay. The parts are shown in Fig. 1 with the lever 26 depressed and the lay in its extreme forward position, the parts assuming this position 80 on every third beat of the lay.

The parts thus far described are of the usual type and form no part of my present invention, which relates particularly to the weft replenishing mechanism and to the provision of means by which it may be maintained in operative relation to the lay, 90 whether the same is forwardly or rearwardly positioned.

A weft carrier magazine 35 of the usual 100 type for multi-color work is shown in the drawings, the magazine comprising a magazine frame 36, an outer bobbin support 37, a thread holder 38, a transerrer 39 and other usual parts associated therewith. A 105 link 40 (Fig. 1) is connected to a bell crank 41 pivoted at 42 on the magazine frame and connecting the bobbin releasing devices with the usual drop box mechanism, not shown. For a detailed description of the magazine 110

and its connection to the drop box mechanism, reference is made to the prior patent to Wyman No. 970,591 issued September 20, 1910.

- 5 The magazine frame 36 is in part supported upon a slide 43 (Fig. 3) mounted in a block or guide-way 44 bolted to the front of the loom frame 10. The slide 43 is preferably of the dove-tailed section shown in Fig. 3
10 and suitable provision is made for maintaining a close sliding fit between the parts. A second slide 45 (Figs. 1 and 2) is mounted to slide in a guide-way or block 46 firmly secured to the loom arch 11.
15 An actuating lever 48 (Figs. 3 and 5) is mounted on a fixed pivot 49 and the forked upper end of the lever 48 engages the elongated end of the shaft or stud 50 upon which the transferrer 39 is pivoted. The lever 48
20 is connected by an adjustable link 51 to an arm 52 secured to one of the cylindrical bearing blocks 17 which support the crank-shaft 16.

Through these connections, the lever 48
25 will be swung on its pivot 49 whenever the bearing of the crankshaft 16 is moved forward or rearward, and a corresponding forward or rearward movement of the magazine 35 will occur. The magazine 35 is thus
30 always positioned in co-operative relation with the shuttle S in the shuttle box 53 (Fig. 1), the magazine moving forward or rearward whenever the locus of movement of the lay is shifted forward or rearward. A
35 weft carrier transfer may thus occur on any beat of the lay provided the desired shuttle S is in the box 53.

I have also provided weft detecting mechanism of a usual type, mounted upon a
40 bracket 54 secured by bolts 55 to the magazine frame and movable forward and rearward therewith. The weft detecting member 56 (Fig. 1) is thus maintained in operative relation with the shuttle in either the
45 forward or rearward adjustment of the lay.

I have thus provided simple and reliable mechanism for maintaining operative relations between the lay and the magazine and parts associated therewith, regardless of
50 changes in the locus of movement of the lay, so that weft carrier transfer will not be subject to interference from such changes in adjustment.

In the specification and claims the term
55 "locus of movement" is used to indicate the limits of movement of the lay when the lay is oscillated and the bearings remain in

some fixed position. When the bearings are moved, the limits of movement are also changed or in other words, the locus of movement is shifted. 60

Having thus described my invention, it will be evident that changes and modifications can be made therein by those skilled in the art within the spirit and scope of my invention as set forth in the claims, and I do not wish to be otherwise limited to the details herein disclosed, but what I claim is:— 65

1. In a loom, a lay, means to shift the locus of movement of said lay forward and rearward, a loom frame, a weft replenishing mechanism movably mounted thereon, and means to move said mechanism forward and rearward to maintain the same in operative relation to said lay. 70

2. In a loom, a lay, means to shift the locus of movement of said lay forward and rearward, a loom frame, a weft replenishing mechanism mounted to slide thereon, and means to slide said mechanism forward or rearward as the locus of movement of the lay is shifted. 75

3. In a loom, a lay, means to shift the locus of movement of said lay, a loom frame, a weft replenishing mechanism movably mounted thereon, and connections from said magazine to said lay-shifting means by which said magazine may be shifted forward or rearward to correspond with a change in the locus of movement of the lay. 80

4. In a loom, a lay, means to shift the locus of movement of said lay forward or rearward, a weft detecting device, and means to maintain said detecting device in operative relation to said lay in all positions of the locus of movement thereof. 85

5. In a loom, a lay, means to shift the locus of movement of said lay forward or rearward, a weft carrier magazine, a thread end holder thereon, and means to maintain said thread end holder in operative position for all changes in lay movement. 90

6. In a loom, a lay, a crankshaft connected thereto, bearings for said crankshaft, automatic means to shift said bearings forward and rearward at predetermined intervals, a weft carrier magazine, and connections between said bearings and said magazine through which said magazine is moved forward and rearward with said bearings. 105

In testimony whereof I have hereunto affixed my signature.

ALBERT A. GORDON, JR.
